UNITED STATES PATENT OFFICE

153,667

DESIGN FOR AN EMBLEM HOLDER FOR AUTOMOBILE RADIATOR GUARD

Leopold Bustin, Mamaroneck, N. Y.

Application October 16, 1947, Serial No. 141,955

Term of patent 3½ years

(Cl. D14—6)

To all whom it may concern:

Be it known that I, Leopold Bustin, a citizen of the United States, residing at Mamaroneck, in the county of Westchester and State of New York, have invented a new, original, and ornamental Design for an Emblem Holder for Automobile Radiator Guard, of which the following is a specification, reference being had to the accompanying drawing, forming a part thereof.

Fig. 1 is a front elevational view of an emblem holder for automobile radiator guard, showing my new design.

Fig. 2 is a top plan view thereof.

The characteristic features of my design reside in the portions shown by means of full lines in the drawing.

I claim:

The ornamental design for an emblem holder for automobile radiator guard, substantially as shown and described.

LEOPOLD BUSTIN.
